Primary Examiner — Karen S Acker*Assistant Examiner* — Clare Ann Gannon(74) *Attorney, Agent, or Firm* — DLA Piper LLP (US)(57) **CLAIM**

The ornamental design for mat, as shown and described.

DESCRIPTION

FIG. 1 is a perspective view of mat showing my new design;
 FIG. 2 is a front elevational view thereof;
 FIG. 3 is a rear elevational view thereof;
 FIG. 4 is a left side elevational view thereof;
 FIG. 5 is a right side elevational view thereof;
 FIG. 6 is a top plan view thereof;
 FIG. 7 is a bottom plan view thereof;
 FIG. 8 is an enlarged detail view of the area in FIG. 6;
 FIG. 9 is an enlarged detail view of the area in FIG. 1; and,
 FIG. 10 is a sectional view taken along line **10-10** in FIG. 9.
 The broken lines on the surface of the design in FIGS. 7 and
 10 depict portions of the surface that form no part of the claimed
 design. The broken lines enclosing the areas of the details are
 not claimed.
